(57) **CLAIM**

The ornamental design of a disposable absorbent liner having an elastic rim for a portable toilet seat and bowl, as shown and described.

DESCRIPTION

FIG. 1 is a perspective view of a disposable absorbent liner having an elastic rim for a portable toilet seat and bowl showing my new design;

FIG. 2 is a front view thereof;

FIG. 3 is a rear view thereof;

FIG. 4 is a side view thereof; the opposite side view being a mirror image;

FIG. 5 is a top view thereof; and,

FIG. 6 is a bottom view thereof.

The fragmentary crisscross pattern shown in the drawing is understood to represent fabric and is repeated uniformly throughout the areas shown.
